7 Claims. (Cl. 81—57)

This invention relates to wrenches, and has particular reference to ratchet wrenches.

The primary objects of the invention are, to provide a wrench having operating means which may be oscillated to cause intermittent rotation in one direction of the wrench head; to provide such a wrench which may also be operated by lateral swinging movement of the handle in the manner of the ordinary ratchet wrench and in which, when so used, the forces automatically balance so that there is no tendency of the handle to rotate in the operator's hand; and to provide such a wrench which may be compactly constructed of few and simple parts, may be easily and cheaply manufactured and assembled, and is particularly adapted and intended for easy and efficient operation on articles disposed in extremely inaccessible places.

In the accompanying drawing:

Figure 1 represents a top plan view, partly in section, of the preferred embodiment of the invention;

Figure 2, a side elevation, also partly in section, of the device shown in Figure 1;

Figure 3, a detail top plan view, partly in section, of one of the rings or rotary drive members of the preferred form of the invention;

Figure 4, a detail top plan view of the wrench head or cylinder of the preferred embodiment of the invention; and

Figure 5, a detail fragmentary view showing a lever or crank fitted into the socket of the operating handle.

Referring now in detail to the accompanying drawing, the body or housing or frame of the preferred embodiment of the invention in which the various moving parts, hereinafter described, are housed or mounted consists of a gear case or housing 1 formed with a preferably cylindrical open ended cavity, said gear case 1 preferably being annular in shape, and a preferably substantially radially extending integral tubular handle casing or housing 3 carried by said gear case 1.

The bore of said tubular handle housing or casing 3 extends through the side of the gear case 1, opening into the cylindrical cavity or bore thereof. Preferably the axis of said handle casing 3 lies at right angles to, and medially intersects, the axis of the cylindrical cavity of casing 1.

Said gear casing or case 1 is formed at either end of its cylindrical gear cavity or bore with means such as radially inwardly extending axially spaced annular bearing shoulders 4 and 6.

In the preferred form of the invention the bottom shoulder or abutment 4 is integral with the

case 1, while the top bearing shoulder or cover 6 is formed in a separate piece to be applied by suitable means, such as cooperating screw-threaded portions 29 formed on said cover 6 and said case 1 respectively, or by spot welding, after the rest of the device has been assembled.

Journalled preferably at its respective ends in said shoulders 4 and 6 so as to extend preferably coaxially through the cylindrical cavitated portion of casing 1 is a cylindrical wrench head 19 formed with a wrench socket 23 preferably extending axially therethrough and being of square or any suitable cross-section, and provided on its exterior curved sides with longitudinally extending integral ratchet teeth 21, the ends of said teeth 21 slidably engaging or abutting against the inner faces of said annular shoulders 4 and 6 respectively to prevent relative axial movement of said wrench head 19 in casing 1.

Freely rotatably journalled in the gear case 1 in the annular space between the outside circumference of wrench head 19 and the radially inner wall of gear case 1 are a pair of rings or ring gears 8 preferably in free sliding contact with each other at their adjacent inner faces, their opposed outer faces being in sliding engagement with the respective inner faces of the annular bearing or retainer shoulders 4 and 6 respectively, it being noted that said shoulders 4 and 6 serve to prevent axial movement both of the ring gears or wheels 8 and of the wrench head 19 in said gear case 1.

In the preferred form of the invention the rings or wheels 8 are provided on their respective adjacent faces with sunken preferably bevelled gear teeth 2, said gear teeth 2 being cut into said rings 8 for only a portion, preferably about a third, of their respective circumferences. The remaining portions of the respective adjacent faces of said gears 8 are preferably formed flat and smooth to slidably contact each other and in operation act as bearing surfaces.

Both of said gears or ring gears 8 of the preferred embodiment are provided with suitable ratchet dogs or pawls 15 having their free or operative ends disposed in the same direction of rotation to in operation engage ratchet teeth 21 of wrench head 19 to cause rotation thereof in that direction, and to respectively disengage said teeth 21 during rotation of said gears 8 in the opposite direction.

The ratchet pawls 15 of the preferred embodiment are each pivotally mounted at one end in cavities 13 formed in the radially inner sides of their respective rings or ring gears 8, the free or

operative ends of said pawls 15 being resiliently pressed into operative engagement with said ratchet teeth 21 by any suitable means, such as small helical or coil springs 17 mounted in said 5 cavities 13.

The operating means of the invention preferably consists of an operating handle or shaft 5 freely rotatably journaled in tubular handle housing or casing 3 and terminating at its inner 10 end with a preferably integral drive pinion 10. Pinion 10 extends radially into the cavitated portion of casing 1 between, and in mesh with, the toothed portions 2 of ring gears 8.

The outer or gripping end of said handle 5 15 preferably projects outward from said casing 3 for a substantial distance and if desired may be suitably knurled or roughened, as shown, to provide a comfortable hand grip for the operator. Also, said handle 5 if desired may be formed 20 at its outer end with suitable means such as an irregular or square cross-sectional crank socket 7 to removably receive the correspondingly shaped end or portion of a suitable lever or crank A, which may be employed to rotate or oscillate said handle 5 in order to obtain powerful leverage and 25 consequent ease of operation.

In order to prevent handle 5 from moving axially too far into the handle casing 3 so that drive pinion 10 carried thereby jams the ring gears or 30 wheels 8, it is desirable to provide means such as stop shoulders 9 and 11 on said handle 5 to abut against the end of handle casing 3 and shoulder 12 respectively of said casing.

Also, if desired, means such as a set screw 25 35 may be disposed through the side of handle casing 3 to extend into an annular groove 27 formed in handle 5 to prevent relative axial movement of said handle 5 in the opposite direction out of said casing 3, or such a set screw may be employed 40 to prevent relative axial movement of said handle 5 in either direction.

The device may be operated in either of two ways, as desired.

In one method of operation, particularly 45 adapted for use where the bolt or other article to be operated on is inaccessible, and it would not be practicable due to lack of room to operate in the manner of the usual ratchet wrench by laterally swinging the handle 5, the operation is as 50 follows:

The socket 23 of the wrench head 19 is placed 55 over the nut or bolt head or other article which is to be rotated or operated upon. Then the handle 5 is vibrated or oscillated, preferably by means of the lever or crank A.

Oscillation of the handle 5 and the drive pinion 10 carried thereby in mesh with ring gears 8 causes simultaneous oscillation in opposite directions of ring gears 8. Thus said rings or ring 60 gears 8 are rotated or partially rotated or oscillated in opposite directions so that the pawls 15 carried thereby will alternately engage ratchet teeth 21 of the wrench head 19 to cause intermittent rotation in one direction of said wrench 65 head 19.

Thus at all times during partial rotation or oscillation of the handle or shaft 5 in either direction one of said ring gears 8 is rotating in the proper direction with its pawl 15 in operative engagement with the wrench head 19 to rotate the same in that direction, while the other of said ring gears 8 is rotating in the opposite direction with its pawl 15 disengaged.

When it is desired to reverse the direction of 70 rotation of the bolt or other article being oper-

ated on it is necessary only to turn the wrench over and engage said article with the opposite end of the socket 23 of wrench head 19.

In addition to the above, the device may be operated in a manner similar to that of the usual 5 ratchet wrench by laterally swinging or vibrating the handle 5. During operation of the device in this manner the pawls 15 will simultaneously engage and disengage the ratchet teeth 21 to rotate wrench head 19, such engagement occurring only during one direction of swinging movement of handle 5.

It should be noted that in such operation by lateral swinging movement of the handle 5 the ring gears 8, due to the simultaneous engagement 15 of their pawls 15 with wrench head 19, tend to rotate in opposition to each other, the opposed equal rotational forces or torques of said gears 8 balancing each other through or by means of the pinion 10 so that there is no tendency of 20 the handle 5 to rotate in the operator's hand.

It may be seen from the foregoing that the device of the present invention, while comprising only a few simple parts, which may be easily and cheaply manufactured and assembled, is capable 25 of several advantageous modes of operation, and is especially adapted for use in a very limited space.

While the construction of the embodiment 30 illustrated is preferred, this however is simply 35 by way of illustration of my invention and it is not essential that the parts be as illustrated.

More in detail, it is not essential that the illustrated arrangement of pawls 15 and ratchet teeth 21 respectively carried by rings 8 and wrench 35 head 19 be employed, it being sufficient if there be provided a part such as head 19 to be rotated, elements such as rings 8 to be oscillated, and means of interengagement between each of said elements and said part whereby the latter may 40 be given an intermittent rotary movement in a single direction due to the alternate oscillations of said elements.

Similarly it is not necessary that either of the flanges or shoulders 4 or 6 be integral, or arranged as hereinbefore described. All that is required is that some suitable means be employed 45 to prevent axial movement of the rings 8 and wrench head 19 while permitting the latter to rotate.

Nor are the stop shoulders 9 and 11, or either of them, essential to the successful operation of the device, though the provision of stop shoulder 9 is highly desired.
